UNITED STATES PATENT OFFICE.

WILLIAM F. HARTIG, OF EVANSVILLE, INDIANA.

CULTIVATOR.

SPECIFICATION forming part of Letters Patent No. 790,300, dated May 23, 1905.

Application filed August 2, 1904. Serial No. 219,191.

To all whom it may concern:

Be it known that I, WILLIAM F. HARTIG, a citizen of the United States, residing at Evansville, in the county of Vanderburg and State 5 of Indiana, have invented a new and useful Cultivator, of which the following is a specification.

This invention relates more particularly to improvements in that type of cultivator described and covered by a prior patent granted to me May 21, 1901, and numbered 674,408.

The object in the present case is to improve the structure of this class of devices by lightening the same in weight, eliminating 15 side draft and the choking of the cultivator, preventing the turning of the shovels and standards on their longitudinal axes, and at the same time permitting the adjustment of the shovels with respect to the beam, so that 20 the cultivated path may be varied in width.

An embodiment of the invention, which is at present considered the preferable one, is illustrated in the accompanying drawings and is described in the following specification.

25 In said drawings, Figure 1 is a top plan view of the cultivator, part of the beam being broken away. Fig. 2 is a side elevation of the cultivator. Fig. 3 is a top plan view, on an enlarged scale, of the cross-bar. Fig.

30 4 is a bottom plan view of said cross-bar. Fig. 5 is a rear elevation of the same. Fig. 6 is a longitudinal sectional view therethrough, taken on the line 6 6 of Fig. 3. Fig. 7 is a detail sectional view through one of the eyes, 35 and Fig. 8 is a detail perspective view of the upper end of one of the standards.

Similar reference-numerals indicate corresponding parts in all the figures of the drawings.

40 In the embodiment illustrated a beam 9 is employed of any suitable configuration, said beam having handles 10 attached to one end and, furthermore, carrying a fender or guard 11, preferably composed of a wire coil having an offset terminal secured to the beam.

45 The cross-bar (designated as a whole by the reference-numeral 12) is in the form of an open frame comprising spaced side members 13, connected by struts 14 and 15, the struts

15 being located in angular relation to one 50 end of the bar and having a web 16 disposed between the same. The side members 13 and struts 14 and 15 are reinforced on their upper sides by ribs 17, certain portions of the under side of the frame or bar being also reinforced by ribs, as 18. A beam-seat 19 extends transversely of the cross-bar and diagonally thereto, said seat having its upper flat face 20 located at an inclination to the longitudinal plane of the cross-bar. The 55 seat 19 is connected to both the side members 13, and the opposite ends of the cross-bar project beyond the opposite sides of said seat. The beam 9 rests flat against the surface 20, and thus the cross-bar will assume a position 60 at an inclination to the horizontal, all of which is fully set forth in the prior patent aforementioned. The beam 9 is connected to the cross-bar by means of a pivot-bolt 21 extending vertically therethrough and 65 through the rear end of the seat. A holding-bolt 22, passing through the beam in advance of the pivot-bolt 21, is arranged to be passed through any of a series of openings 23, located in the front end of the seat, said series being disposed concentrically to the 70 pivot-bolt.

In the present embodiment the means for connecting the standards to the cross-bar are in the form of eyes 24, having standard-receiving seats and located alongside the rear side member 13 of said cross-bar, the eyes 24 being connected to the cross-bar by means of stems 25.

The eyes have sockets 26 in their under 85 sides, and opening from the rear side of said sockets are seats 27. The standards (designated 28) employed in connection with this structure are similar in all respects with those shown in a design patent granted to me July 30, 1901, and numbered 34,869. Said standards have their main portions curved and provided with longitudinally-disposed ribs, one of said ribs, as 29, extending rearwardly. The upper portion of the standards, as 30, 90 are vertically disposed and are adapted to be received in the sockets 26, said upper portions having vertically-extended threaded

shanks 31, that pass through the eyes and receive holding-nuts 32. The openings through the eyes are disposed perpendicularly with respect to the upper surface 20 of the beam-seat, and surrounding said openings are flanges 33, the upper faces of which are parallel to the face 20. Thus the standards will be disposed vertically notwithstanding the inclination of the cross-bar. The ribs 29 of the standards have their upper ends disposed in the seats 27 of the eyes, and this interlocking engagement serves to prevent the rotation of said standards in said eyes.

The present structure while possessing all the advantages of that illustrated in the prior patent, No. 674,408, has others of an important nature that are absent from said other structure. In the first place it is to be noted that this cross-bar may be cast in one piece and while very light in weight is thoroughly strengthened to withstand the strains brought against it. It will also be observed that because of the particular construction the central eye can be placed in line with the bolts 21 and 22, while the outer eyes are located at substantially equal distances on opposite sides of the same. Thus side draft is eliminated with all its consequent objections. At the same time by swinging the cross-bar with respect to the beam and again fastening it the path of travel of the shovels can be made wider or narrower. Another important advantage resides in the arrangement of the standards with respect to the cross-bar. By having the eyes located in rear of the same open spaces are provided between their upper ends which allow the escape of material caught by the standards and forced upwardly. The result is that the cultivator will not become as readily choked and deeper plowing can be successfully done. Furthermore, because of the interlocking connection between the upper ends of the standards and the eyes the plows will always maintain their proper positions and will not be turned sideways.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. As an article of manufacture, a cultivator-bar having a transversely-disposed beam-seat, and spaced integral stems projecting from one side of the bar and terminating in standard-receiving eyes, the tops of said

eyes terminating below the plane in which the beam-seat is located.

2. As an article of manufacture, a cultivator-bar having a transversely-disposed beam-seat on its upper side, said bar being furthermore provided with a plurality of integral standard-receiving eyes projecting from one side of the same and having their upper faces disposed in a plane or planes lower than that in which the seat is located.

3. As an article of manufacture, a cultivator-bar having a transversely-disposed beam-seat, the bearing-surface of which is disposed at an inclination to the bar, said bar carrying a plurality of integral standard-receiving eyes projecting from one side of the same, the axis of said eyes being substantially perpendicular to the surface of the seat, and said eyes having bearing-surfaces surrounding the openings and located substantially parallel to the said surface of the seat.

4. As an article of manufacture, a cultivator-bar having a transversely-disposed beam-seat on its upper side, said bar being furthermore provided with a standard-receiving eye, said eye and seat being located one directly behind the other, and the eye having its top disposed below the plane of the bearing-surface of said seat.

5. The combination with a beam, of a cross-bar located at an inclination to the beam, a transversely-disposed beam-seat carried by the cross-bar on which said beam rests, spaced bolts connecting the cross-bar and beam and passing through the seat, and standard-receiving eyes located in rear of and connected to the cross-bar, one of said eyes being located in line with and in rear of the beam-seat.

6. The combination with a beam, of a cultivator cross-bar, a beam-seat extending transversely of the cross-bar and bearing against the beam, said bar projecting on opposite sides of the seat, a pivot-bolt passing through the beam and seat, and a holding-bolt passing through the beam and having an adjustable connection with the seat in spaced relation to the pivot-bolt.

7. The combination with a beam, of a cultivator cross-bar extending transversely of the beam and located at an inclination thereto, a beam-seat disposed transversely of the cross-bar, a pivot passing through the rear end of the seat and through the beam, a holding device passing through the beam and having an adjustable connection with the front end of the seat, and a plurality of standard-receiving eyes extending along the rear side of the cross-bar.

8. The combination with a cultivator-bar having an eye provided with an offset seat, of a standard engaged in the eye and having a projecting portion engaged in the seat.

9. The combination with a cultivator

cross-bar having an eye, said eye being provided with an offset seat, of a standard having a rearwardly-projecting rib and an upstanding shank, said shank engaging in the eye and said rib engaging in the seat.

10. The combination with a cultivator cross-bar, of rearwardly-extending eyes connected to and located alongside of the rear side of the bar, said eyes having sockets in their under sides and provided with offset seats, and ribbed standards secured in the eyes engaging in the sockets, certain of the ribs of said standards engaging in the seats and holding the standards against turning in the eyes.

11. The combination with a cross-bar comprising longitudinally-disposed spaced side members and spaced angularly-disposed struts connecting the same, of a beam-seat

connecting the side members, and means for attaching standards to the cross-bar.

12. A cultivator cross-bar comprising an open frame, said frame being provided with strengthening-ribs, a transversely-disposed beam-seat located at an inclination to the cross-bar, said seat having a pivot-receiving opening at one end and a plurality of openings at the other adapted to receive a holding-bolt, and a plurality of spaced eyes projecting from one side of the frame.

In testimony that I claim the foregoing as my own I have hereto affixed my signature in the presence of two witnesses.
